UNITED STATES PATENT OFFICE.

HARRY A. MAYBERRY, OF MCLEANSBORO, ILLINOIS.

CAR-SIGN EXHIBITOR.

1,380,001.

Specification of Letters Patent. Patented May 31, 1921.

Application filed August 17, 1920. Serial No. 404,134.

To all whom it may concern:

Be it known that I, HARRY A. MAYBERRY, a citizen of the United States, and a resident of McLeansboro, in the county of 5 Hamilton and State of Illinois, have invented a new and useful Car-Sign Exhibitor, of which the following is a specification.

My invention relates to street or railway 10 car sign exhibitors and has as its all important object the provision of a sign exhibiting apparatus which will indicate to the passengers of a car, the street that is being approached.

15 Further, the invention provides an automatic street indicator for street or railway cars which will successively indicate the various streets approached by the car at a sufficient distance in advance of the streets 20 to give the passengers time to signal that they desire to leave the car at the next stop.

The invention also provides an electrically operated automatic street indicator of this character including a motor and a novel 25 circuit maker and breaker for operating the motor at predetermined times.

With the preceding and other objects and advantages in mind, the invention consists in the novel combination of elements, constructions and arrangement of parts, operations and specific features which will be 30 hereinafter enlarged upon, claimed and illustrated in the accompanying drawings, wherein:

35 Figure 1 is a fragmentary view, partly in elevation and partly in vertical cross section of a car equipped with the invention;

Fig. 2 is an enlarged view of an exhibitor removed from the car, parts being broken 40 away;

Fig. 3 is an enlarged fragmentary vertical sectional view of the circuit maker and breaker embodied in the invention;

Fig. 4 is a fragmentary front elevation of 45 the trolley pole and shoe and one of a plurality of contacts arranged at predetermined intervals for engagement by the shoe; and

Fig. 5 is a diagrammatic view of the electric circuit embodied in the invention.

Referring to the drawings in detail wherein like characters of reference designate corresponding parts throughout the several 55 views, the numeral 5 designates a street car of usual construction embodying a trolley pole 6 to the upper end of which an out-

standing electric contact or shoe 7 is attached.

The trolley or feed wire is designated at 8 and connected with this feed wire 8 at predetermined intervals, such as between two street crossings or stations and intersecting the feed wire 8, is a branch conductor 9 from which depends a contact 10 to be engaged by the shoe 7 upon advance of the 60 car. Arranged within the car 5 and preferably at the forward end thereof within sight of the passengers is a casing 11 provided with a sight opening 12. Horizontally disposed shafts 13 and 14 are journaled in the casing 11, each of which carries a roller 15, and passing around these rollers 15 is an endless sheet or belt 16 having the numbers or names of the streets 65 consecutively arranged thereon in the order in which they are approached.

Supported on a suitable bracket 17 arranged at the upper end of the casing 11 is an electric motor 18 in circuit with the car lighting system indicated in its entirety at 70 19. A shaft 20 extends from the motor 18 and has one end journaled in one of the side walls of the casing 11, and fixed to the shaft 20 adjacent its opposite end are clutch elements 21 and 22. A relatively long sleeve 75 23 is slidably mounted on the shaft 20 and fixed to one end of the sleeve is a clutch element 24 to be engaged with the clutch element 21 and fixed for rotation with the clutch element 24 is a drive pulley 25 about 80 which a drive belt 26 is engaged, the latter passing around a drive pulley 27 fixed to one end of the shaft 13 whereby the lower roller 15 is driven in one direction to move the endless sheet or belt 16 in one direction 85 90 to successively exhibit the signs.

A clutch element 28 is fixed to the opposite end of the sleeve 23 and is adapted for engagement with the clutch element 21 when the pulley 25 is allowed to be idle on 100 the shaft 20. This clutch element 28 carries a drive pinion 29 meshing with a gear 30 carried by a clutch element 31 slidable on a shaft 32 arranged below the shaft 20 and having one end journaled in a bracket 105 33 depending from the upper wall of the casing 11 and its opposite end journaled in a partition wall 34 of the casing 11.

The sleeve 23 carries a depending arm 35 adjacent its inner end which is rigid with 110 the clutch element 31, the latter being engaged with a clutch element 36 on the shaft

32 when the pulley 25 is idle, at which time the gear 30 is in mesh with a pinion 37 fixed to the shaft 14. Slidably mounted in one of the side walls of the casing 11 at 5 its upper end is a sleeve 38 provided with an operating knob 39. This sleeve 38 overlies one end of the shaft 20 and has its inner end enlarged and connected to the clutch element 24 by a yoke 40.

10 It will be manifest that upon moving the sleeve 38 outwardly the sleeve 23 will be moved to disengage the clutch elements 21 and 29 and the clutch element 24 engaged with the clutch element 22 to drive the pulley 25 to drive the shaft 13 in one direction and that upon moving the sleeve 38 inwardly, driving connection will be established between the clutch elements 21 and 29 to drive the shaft 14 reversely through the 20 pinions and gears above mentioned.

In order to operate the motor 18 at pre-determined intervals I provide a circuit maker and breaker which includes a disk 41 fixed to rotate with the shaft 32 and is 25 provided with a laterally disposed circumferential flange 42. An L-shaped trip 43 is pivoted to the disk 42 at its peripheral edge and one leg thereof normally rests upon the flange 42. A spring 44 engages the trip 43 30 at its pivot and normally holds the same at a slight tangent with respect to the disk.

Secured to the bracket 33 is an outstanding plate 45 from which a relatively long electric contact 46 depends. A movable 35 contact 47 is pivoted to the plate 45 and is normally urged toward the contact 46 by a contractile spring 48 having its ends secured to both contacts. Conductors 49 in circuit with the lighting circuit indicated at 40 19 are electrically connected with the contacts 46 and 47 while conductors 50 in circuit with the lighting system 19 are electrically connected with an electro-magnet 51 supported on a bracket 52 secured to one 45 of the side walls of the casing 11. The upper end of the bracket 52 is beveled, and fulcrumed on this end is an armature 53 normally retained in a horizontal position and in the path of one leg of the L-shaped 50 bracket 43 by a coil spring 54 having one end secured to the armature and its opposite end secured to the bracket.

Assuming the parts are in the positions shown in Fig. 3 and that the shoe 7 carried 55 by the trolley pole 6 engages one of the contacts 10, a circuit will be completed through the coil or magnet 51 attracting the armature 53 to dispose the forward end of the same out of the path of the trip 43, the 60 contact 47 acting under the influence of the spring 48 is then engaged with the stationary contact 46 completing the circuit through the motor 18 to drive either the shaft 13 or 14 depending upon the relative 65 position of the clutches above set forth.

When the disk 42 has made one complete revolution the sign sheet will have been advanced sufficiently to dispose one of the signs in the sight opening 12 and at this time the trip 43 will engage the end of the 70 movable contact 47 and move the same away from the stationary contact 46 to break the circuit to the motor and as the armature 53 has been returned to its normal position through the medium of the spring 54, the 75 parts will be held in their normal position ready for the next operation.

It is to be understood that the form of my invention herein shown and described is to be taken as a preferred example of the same, 80 and that various changes in the shape, size and arrangement of parts may be resorted to without departing from the spirit of the invention or the scope of the subjoined claims.

Having thus described my invention, what 85 I claim as new and desire to secure and protect by Letters Patent of the United States, is:

1. A street car sign exhibitor including a 90 casing, a pair of rollers journaled therein, an endless sign sheet passing around the rollers, an electric motor, means between the motor and rollers to advance the sheet in either direction, fixed and pivoted contacts in circuit with the motor and the electrical system of the car, a disk rotated by the motor and normally at rest, a trip pivoted to the disk and normally holding the pivoted contact away from the fixed contact, a magnetically operated element in the path of the 95 trip and in circuit with the motor and normally retaining the trip in a position to hold the pivoted contact against movement, and means for operating the magnetically 100 operated element at predetermined times to allow the trip to move to permit the pivoted contact to engage the fixed contact to establish an electric circuit to the motor to advance the sign sheet, the pivoted contact being moved away from the fixed contact by 105 the trip upon completion of one revolution of the disk and the magnetically operated element being returned to its normal position to lock the trip against movement.

2. A street car sign exhibitor including a 110 casing, a pair of rollers journaled therein, an endless sign sheet passing around the rollers, an electric motor, means between the motor and rollers to advance the sheet in either direction, fixed and pivoted contacts 115 in circuit with the motor and the electrical system of the car, a disk rotated by the motor and having a laterally disposed circumferential flange, an L-shaped trip pivoted to the disk and having one leg adapted to engage the flange to limit the movement of the trip in one direction, stationary and pivoted contacts, the pivoted contact being normally held away from the fixed contact by the trip, 120 a magnet at one side of the disk, a normally 125 held contact at the other side of the disk, the 130 magnet being normally held in position by the 135 spring 54.

horizontally disposed armature having one end disposed in the path of the lateral leg of the L-shaped trip to hold the same against pivotal movement, and electrical means for attracting the armature to the magnet at predetermined intervals to permit the trip to rock forwardly to allow the pivoted contact to engage the stationary contact to establish an electric circuit to the motor to advance the sign sheet, the pivoted contact being moved away from the stationary contact by the trip upon the completion of one revolution of the disk to stop the motor.

3. A sign exhibitor including a casing, a pair of rollers journaled therein, a sign sheet engaged with the rollers, an electric motor operatively connected with the rollers, a disk rotated by the motor, electrical means for rendering the motor operative at predetermined periods to advance the sign sheet and including fixed and movable contacts, a trip carried by the disk and holding the movable contact away from the fixed contact while the motor is inoperative, the trip being moved away from the movable contact to permit the latter to engage the fixed con-

tact to close an electric circuit to the motor upon actuation of said electrical means.

4. A sign exhibitor including a casing, a pair of rollers journaled therein, a sign sheet engaged with the rollers, a motor for driving either one of the rollers to advance the sign sheet, a circuit to the motor, means for supplying electrical energy to the motor at predetermined periods, fixed and pivoted contacts in the circuit, a disk rotated by the motor, a pivoted trip carried thereby and normally holding the pivoted contact away from the fixed contact to render the motor inoperative, and a pivoted magnetically operated member in the path of the trip and in the motor circuit and normally retaining the trip in a position to hold the pivoted contact against movement, said member upon being operated permitting the trip to move to a position to allow the pivoted contact to engage the fixed contact to complete the circuit to the motor to advance the sign sheet.

HARRY A. MAYBERRY.
